UNITED STATES PATENT OFFICE.

MORRIS ANDERSON, OF JAMESTOWN, NEW YORK.

SHEET-METAL CONSTRUCTION.

1,062,210.

Specification of Letters Patent. Patented May 20, 1913.

Application filed April 7, 1911. Serial No. 619,508.

To all whom it may concern:

Be it known that I, MORRIS ANDERSON, a subject of the King of Sweden, and resident of Jamestown, county of Chautauqua, 5 and State of New York, have invented new and useful Improvements in Sheet-Metal Construction, of which the following, taken in connection with the accompanying drawings, is a specification.

10 The invention relates to improvements in sheet metal construction, particularly to sheet metal seams; and the object of my improvement is to provide an interlocking seam which it is practically impossible to 15 open under extreme heat, and the invention consists in the construction and arrangement of the parts and its adaptation to the different parts of a sheet metal door or window, as described in this specification and shown 20 in the accompanying drawings and pointed out in the claim.

The hollow sheet metal construction has proved inadequate in its fireproof qualities on account of the seams separating or opening under intense heat or by accident. 25 My improved sheet metal construction as herein described provides a simple, durable construction in which the seams are so locked that they cannot separate, and the door is 30 so put together that it forms a perfect sheet metal fireproof closure for a compartment and it is apparent that this locked seam is applicable to all forms of sheet metal fireproof fittings, including sheet metal 35 doors, windows and the casings for the same.

In the drawings Figure 1 is an elevation of a sheet metal door. Fig. 2 is a sectional view at line X X in Fig. 1, showing the locked seam at each side and the manner of 40 mounting a plate of glass either in the upper part of the door or in a sheet metal window. Fig. 3 is a sectional view at line Y Y in Fig. 1, showing the construction for holding a sheet metal panel with the improved seam at each side of the stile; and Fig. 4 is a similar view showing a modification of the construction shown in Fig. 3 with the locking seam each side of the panel, the locking ends of the seam serving as a holding means for the sheet metal panel; in most cases this latter form is 50 preferred; and Fig. 5 is a still further modification of the construction at line Y Y showing the adaptation of the seam construction to a continuous panel and molding. Fig. 6 is a detail sectional view of

the separated edges of the sheet metal as formed to slide together into the improved seam for the abutting edges as shown at line Z Z in Fig. 1; and Fig. 7 is a sectional view of the completed seam after the parts are slipped together. Fig. 8 is a sectional view of a double or two-way seam for abutting edges, showing the double lock upon the same; and Fig. 9 is a sectional view of a single-way seam having a double lock; these modifications shown in Figs. 8 and 9 may be used in place of the seam shown in Figs. 6 and 7, to give added security in heavy doors. Fig. 10 is a sectional view at line Y Y showing the use of the seams the same as in Fig. 3, in connecting the molding to the stiles and also showing the turned edge locking principle applied to the edges of the panel sheets, a box being formed in the groove between the moldings to receive said locking edge. Fig. 11 is a sectional view at line Z Z for a double-way seam for heavy doors to hold the stiles and rails a spaced distance apart; and Fig. 12 is a sectional view at line Z Z of a multiplication of this double seam construction for heavy doors to hold the stiles and rails a fixed distance apart so that they cannot be separated.

Like numerals of reference refer to corresponding parts in the several views.

The numeral 10 indicates the hollow sheet metal stile, the numeral 11 the molding and the numeral 12 the sheet metal panel. The 90 seam 15 consists of a return bend sheet metal seam and the improvement consists in turning the edge of the sheet metal both in the looped part 13 and the edge 14 of the return bend which enters into the looped portion and forms a seam 15, as shown in Fig. 6, so that the two may be slipped together, as shown in Fig. 7, and it is obvious that when so slipped together and placed under heavy pressure the entire seam will be 95 locked in place so that neither accident nor intense heat can force the two edges apart. For added security in certain kinds of sheet metal, a double or two-way seam as shown at 16 in Fig. 8 having the two turned or locking ends is used, or this turned edge of the seam may be applied to a single-way seam in the double locking form, as shown at 17 in Fig. 9. It is apparent that either of these two-way seams shown in Figs. 8 100 and 9 can be pressed into place by means of a suitable die and press. This locking prin-

2

5 principle of the turned seam is shown in the
10 seams between the molding and stiles in
15 Figs. 2, 3, 5, 10 and 11 and forms a cheap
20 and convenient means for affording absolute
25 security against separation of these
30 seams. This same principle may be utilized
35 also in holding the panel 12 by extending
40 the edges of the sheet metal panel around
45 the outwardly turned ends 18 as shown in
50 Fig. 4, thereby making the locked seam each
55 side of the edge of the sheet metal panel 12
60 in such a manner as to absolutely prevent
65 the separation of the sheet metal panel from
70 the hollow stile 10. This form of construction
75 is preferably used in light doors. For
80 heavy doors the modifications shown in Fig.
85 10 may be used which applies still further
90 this locking principle at 19. The groove 21
95 as shown in Fig. 3 is formed with a box at
100 its inner end and the edges 22 of the sheet
105 metal panels 12 are turned in a locking closure
110 within said box, said edges 22 stop at
115 each side of the box.

120 In order to hold and brace the sides of
125 the door a spaced distance apart, particularly
130 in heavy doors, the two-way seam shown in Fig. 8 is preferred, and the locking
135 strip is formed on one side in its central
140 portion by an extension 24 having a dove-
145 tail-shaped end 25. The strip 26 on the
150 opposite side is formed with oppositely placed
155 flanges 27 which form a dove-tail-shaped
160 opening therebetween, into which the dove-
165 tail-shaped edge 25 of extension 24 is
170 slipped, thereby holding the two parts
175 firmly in position and bracing the sides of
180 the door so they cannot be separated or
185 changed in their relation to one another.
190 It also braces these two sides of the door at

195 the point of the abutting seam between the
200 two parts, as for example, between the stiles
205 and cross rails, which will be recognized as
210 the weakest portion of the hollow door construction.
215 The locked seam is also used for the
220 connection of the molding to the stiles
225 in holding the glass panels 28 in which
230 construction the molding is formed for one side
235 only and a loose molding 29 is attached by
240 a suitable screw 30 within the angle on the
245 opposite side of the glass 38, as shown in
250 Fig. 2.

255 It is obvious that all of these parts may
260 be easily formed with suitable dies and
265 slipped together into the forms shown, and
270 when so slipped together may be spot
275 welded or acetylene welded if so desired.

280 I claim as new:

285 In a sheet metal door, stiles and cross
290 rails, oppositely placed seams on the oppo-
295 site sides of the door to connect said parts
300 having inwardly and oppositely turned
305 edges, a binding strip fitting over said oppo-
310 site turned edges to hold the same, the
315 edges of said seams turned in angular flanges
320 to lock the same against withdrawal, said
325 binding strips having grooves bent therein,
330 and a strip of metal fitting within said
335 grooves on the oppositely placed binding
340 strips to hold said parts a spaced distance
345 apart.

350 In testimony whereof I have signed my
355 name to this specification in the presence of
360 two subscribing witnesses.

365 MORRIS ANDERSON..
